UNITED STATES PATENT OFFICE.

JAMES MONTGOMERY, OF CROTON LANDING, NEW YORK.

IMPROVED RAILWAY-RAIL.

Specification forming part of Letters Patent No. 97,792, dated December 14, 1869.

To all whom it may concern:

Be it known that I, JAMES MONTGOMERY, of the city, county, and State of New York, have invented certain new and useful Improvements in Railways and Rails therefor; and I do hereby declare the following to be a full, clear, and exact description of the same, reference being had to the accompanying drawings, making part of this specification, and in which—

Figure 1 is a plan of one rail of my railway-track, shown partly in horizontal section. Fig. 2 is a vertical longitudinal section thereof. Fig. 3 is a transverse section of the same. Figs. 4, 5, 6, and 7 are transverse sections, illustrating a modification in the construction of the rails and different modes of securing them in position. Fig. 8 is a transverse section on a large scale, showing more clearly the preferred form of tongue-and-groove joints. Fig. 9 illustrates a modification in the form of the longitudinal rail-joint hereinafter described.

Similar letters of reference indicate corresponding parts in the several views.

My invention consists, first, in the construction, substantially as hereinafter described, of a hollow rail of steel or other metal, either with or without the described longitudinal joints, with its top and bottom made thick for strength and its sides tapering toward the vertical center for lightness; second, in a device for securing such rails in position; third, in hermetically closing the longitudinal and transverse joints of the rails, so that they may be used for containing telegraph-wires, for conducting water for the supply of locomotives, for pneumatic transportation-tubes, or for other purposes; fourth, in a peculiar manner of forming a permanent joint in the rails.

In the drawings, A represents my tubular rail, which I prefer to construct without longitudinal joints by rolling from a hollow ingot of steel by means of suitable machinery, which will form the subject of a separate application for Letters Patent. By thus rolling the bar from a hollow ingot the fibers of the metal are drawn out longitudinally in all parts of the bar in such a manner as to impart to it greater tensile strength.

In order to utilize the hollow interior of the rail for various purposes, it may be constructed, either at intervals or throughout, with longi-

tudinal joints, as shown in Figs. 4 to 9, inclusive. The rail, whether jointed or not, may be made with vertical sides, as in Fig. 3, or with flanges.

In order to afford uniform support to the rails throughout their length, I prefer to recess them into longitudinal sleepers or string-pieces C, either jointed longitudinally, as shown in Figs. 1, 2, and 3, or unjointed, as in Figs. 4 and 6, and the said stringers may be notched into cross-ties D. The continuous support afforded to the rails by the string-pieces is also beneficial in preserving them from breaking in frosty weather, and also avoiding the uneven motion caused by the springing of the rails between transverse ties.

If preferred, the rails may be applied directly to the cross-ties D and the stringers C beneath the ties, as illustrated in Fig. 5; or the rails may be supported vertically by the ties D and laterally by the stringers C, as shown in Fig. 7.

E E represent bolts, provided with nuts E', and applied in any suitable manner to clamp the rails firmly in position. In Fig. 4 the nut E' is shown as introduced into a recess in the cross-tie. For use in this way the nut will be made of oblong shape, to prevent it from turning in the wood, and the wrench will be applied to the head of the bolt.

F F are metallic knees, which may be used in connection either with the bolts E, as shown in Figs. 5 and 6, or with barbed or other spikes G, as shown in Fig. 7, to support the inner side of the rail.

By forming the tongues a, as shown in Fig. 8, straight at the base and tapering toward the edge, and the grooves b of corresponding shape, the tongues are adapted to enter the grooves with facility, and when they are wedged into position by cramping the rails between rolls or with any other suitable machinery the parallel parts of the tongues and grooves form a joint which cannot be separated without great force. I propose to apply to the joints before closing coal-tar or other suitable material to make them air and water tight, and also to form a stronger connection.

In Fig. 9 is represented a peculiar dovetail joint, which I produce by forming the groove first as indicated by dotted lines, and after the two parts of the rail are put together closing the groove upon the dovetail tongue by

means of powerful rolls, a mandrel being employed to close the inner flange of the dovetail.

H is a thimble recessed into the ends of the rail-sections, and forming a coupling between them. Instead of thus employing a separate thimble, the joint can be formed in the rail-sections themselves by recessing one end and reducing the other by means of suitable machinery. A packing of india-rubber or other suitable material will be applied to form an air and water tight joint while providing for the longitudinal motion due to the expansion and contraction of the rails under changes of temperature. The longitudinal joints may also be packed with india-rubber, either in the form of flat strips or in cylindrical cords fitted in grooves in the faces of the rail.

In practice I prefer to incline my rails inward at such an angle that the major axis of the ellipse will be in line with the resolution of forces between the vertical and lateral pressure and blows of the wheels. This inclination should, I suppose, be about thirty degrees from the perpendicular; but it can be determined more accurately by experiment.

I I I represent telegraph-wires supported within the rail by disks J of glass or other insulating material. The insulators J are formed with flanges, to retain them in their proper vertical position. K K represent "test-holes," through which a suitable instrument may be inserted in contact with either of the wires to ascertain whether they are in effective condition.

Of the four rails constituting a double-track railway, I propose to employ two for pneumatic-dispatch purposes for conveying in opposite di-

rections, one for the telegraph-wires, and one as a water-pipe, which may be connected with natural supplies of good water wherever they exist along the road, and may be furnished at suitable intervals with couplings and taps, with which a feed-pump on the locomotive may be connected, so as to make the locomotive pump its own water. If preferred, water-tanks may be used, the water-conducting rail being still useful as a means of conveying good and pure water from wherever it may be found to the various water-stations. Where a "head" of water exists in the tubular rail, this may be used to elevate it into the tender or into a stationary reservoir.

Having thus described my invention, the following is what I claim as new therein and desire to secure by Letters Patent:

1. A tubular rail rolled in one piece and composed of a single bloom or ingot, having an aperture through it of such shape and dimensions and so located as to leave the largest amount of metal at top and bottom, (the points against which the wheels bear,) the vertical or nearly vertical sides being parallel to each other.
2. Mounting tubular steel rails in string-pieces C, from which they derive both vertical and lateral support, and securing them by bolts E, applied in any manner, substantially as set forth.
3. The dovetail joints represented in Fig. 9, formed in substantially the manner described.

JAMES MONTGOMERY.
